UNITED STATES PATENT OFFICE.

HARRY BECKWITH, OF NEW CASTLE, PENNSYLVANIA.

HORN OR BELL ATTACHMENT.

1,278,095.

Specification of Letters Patent. Patented Sept. 10, 1918.

Application filed October 18, 1917. Serial No. 197,319.

To all whom it may concern:

Be it known that I, HARRY BECKWITH, a citizen of the United States, residing at New Castle, in the county of Lawrence and State 5 of Pennsylvania, have invented certain new and useful Improvements in Horn or Bell Attachments, of which the following is a specification.

This invention relates to a horn or bell 10 attachment and has for its principal object the production of a device which is removably mounted upon a horn or bell for harmonizing the secondary tones thereof although increasing the volume of the device.

15 Another object of this invention is the production of a horn or bell attachment which consists of a casing supported upon the horn or bell to receive and project a secondary sound of the horn or bell thereby 20 harmonizing although increasing the volume of the tone of the horn or bell upon which the structure is carried.

Another object of this invention is the 25 production of a horn or bell wherein the casing is substantially cylindrical and is provided with a head at one end thus allowing the attachment to be positioned upon a horn or bell, although the flared end portion of the attachment will permit the sound waves 30 to be projected therefrom, thus harmonizing the tones and sound waves of a horn or bell upon which the same is carried, although increasing the volume of these waves.

A still further object of this invention is 35 the production of a washer which is mounted upon the horn or bell and fixedly bears upon the casing for holding the same against accidental movement after being positioned upon the horn or bell.

40 With these and other objects in view, this invention consists of such novel combinations, constructions, and arrangement of parts and will hereinafter be fully described and claimed.

45 Several practical forms of embodiment of the present invention are shown and described, in the accompanying drawings, in which—

50 Figure 1 is a central longitudinal section through the horn or bell attachment showing the same mounted upon a horn.

Fig. 2 is a longitudinal section through the attachment illustrating the same mounted upon a bell,

Fig. 3 is a longitudinal section through the 55 invention mounted upon a horn, and

Fig. 4 is a transverse sectional view through the device shown in Fig. 3.

Referring to the accompanying drawing by numerals, and particularly to Fig. 1, it 60 will be seen that the attachment is mounted upon a horn which comprises the usual conical body 1 having a bell 2 thereon.

The attachment comprises a cylindrical casing 3 having a closed head 4 at its inner 65 end. This head 4 is provided with a central opening 5 surrounded by the conical sleeve 6. The opposite end of the casing 3 is provided with a bell 7. The horn body 1 is passed through the casing 3 and projects beyond the sleeve 6. Owing to the fact that 70 this sleeve 6 is conical in form, as shown in Fig. 1, it will bind upon the horn body 1 for fixedly retaining the casing in an adjusted set position. At this time the bell 7 75 of the casing 3 will be spaced from the bell 2 of the horn body 1. As a result, the secondary tones and sound waves vibrating from the horn body 1 and the bell 2 will be received and modified within the casing 3 to 80 be harmonized, although the closed construction of the inner end of the attachment will cause these sound waves to be projected therefrom in an increased volume, passing between the bell 2 and 7.

85 By referring to Fig. 2, it will be seen that the bell 8 is provided with an enlarged lower end 9, as is the usual construction of bells. The casing 10 is provided with a bell or flared portion 11, while the head 12 is 90 formed integral upon the casing 10. This head 12 is provided with a central opening 13 through which the retaining lugs or elements 14 of the bell 8 project. For this reason a head 12 will bear upon the upper 95 end of the bell 8 and cause the attachment to be supported so that the bell or flared portion 11 of the casing 10 will be spaced from the enlarged portion 9 of the bell 8. The secondary tones and sound waves vibrating 100 and proceeding from the bell 8 will be received in the casing wherein they will be harmonized and then projected in an increased volume from the outer end of the casing, by passing between the enlarged portion 9 of 105 the bell 8 and the bell or flared portion 11 of the casing 10.

By referring to Figs. 3 and 4, it will be

seen that the bell 8 is provided with an enlarged lower end 9, as is the usual construction of bells. The casing 10 is provided with a bell or flared portion 11, while the head 12 5 is formed integral upon the casing 10. This head 12 is provided with a central opening 13 through which the retaining lugs or elements 14 of the bell 8 project. For this reason a head 12 will bear upon the upper end 10 of the bell 8 and cause the attachment to be supported so that the bell or flared portion 11 of the casing 10 will be spaced from the enlarged portion 9 of the bell 8. The secondary tones and sound waves, 15 and proceeding from the bell 8 will be received in the casing wherein they will be harmonized and then projected in an increased volume from the outer end of the casing, by passing between the enlarged portion 9 of the bell 8, and the bell or flared portion 11 of the casing 10.

By referring to Figs. 3 and 4, it will be seen that the conical formed body 18, is provided with the usual bell portion 2'. The 25 cylindrical casing 16 is provided with a bell portion 17 adjacent one end while a head 15 is formed upon the opposite end of the casing 16. This head 15 is provided with a central opening 15' surrounded by the 30 conical sleeve 18, whereby the horn body 1' may be passed through the opening 15' and may engage the conical sleeve 18 for assisting in retaining the casing in an adjusted set position upon the horn.

35 It may be desired, or necessary, to provide an additional retaining means for holding the attachment against displacement and for this reason the washer 19 having a central opening 20 is positioned upon the horn body 1', as illustrated in both of the last 40 mentioned figures. This washer 19 is provided with a plurality of sound perforations 21 formed therethrough, as shown clearly in Fig. 4, for allowing the sound waves to 45 pass through the opening and be projected from the attachment when the same is in use. This washer 19 is positioned upon the horn body 1' and then the attachment is positioned as indicated in Fig. 3. As the 50 attachment is wedged onto the washer 19, and owing to the conical construction of the horn body 1' it is obvious that the casing will be positively held against accidental displacement. The sound waves caused by 55 the vibration of the horn will be received within the casing and to the closed end of the inner end of the casing, will proceed through the openings or perforations 21 formed in the washer 19 to be finally projected between the bell 17 of the attachment and the bell 2' of the horn.

60 It is of course obvious that the attachment herein shown may be connected to horns and bells of motor vehicles, or may 65 be of such size as to be mounted upon the

horns of orchestra and band instruments, as well as to horns and bells of any and general construction. It should of course be understood that the attachment may be made of any desired length, such for instance as will synchronize the pulsations of air within the casing with the vibration of the flaring bell. Furthermore, should the device be used, as suggested in Fig. 3, for instruments of orchestra and band nature, 70 the length of the casing must correspond to the pitch of the horn, being shorter for high pitched tones, as sound wave lengths are shorter in high tones although longer in low tones and for this reason the attachment must be of the proper length necessary to produce the volume and tone desired.

It is obvious that many minor detail changes may be made in the construction of the present invention, say for instance as 85 the length and shape of the device, without departing from the spirit of the invention and for this reason it is not intended to limit the construction of this horn or bell attachment to the specific forms herein 90 shown, as it is intended to include all such forms of the invention as properly comes within the scope of the invention as claimed.

What is claimed is:

1. A horn or bell attachment comprising a casing, said casing having a head formed upon one end, said head having an opening formed therethrough, a conical flange formed upon said head and surrounding said opening, the opposite end of said casing being flared to form a bell, a disk positioned within said casing and having a central opening, said disk also having sound perforations formed therethrough whereby a horn may be projected through the opening of said disk and through said sleeve for allowing said sleeve and disk to grip the horn for holding said attachment against displacement, while the attachment will receive and harmonize and project with increased volume the secondary sound waves issuing from the horn. 105

2. A horn or bell attachment comprising a casing, said casing having a head formed upon one end, said head having an opening formed therein, the opposite end of said casing being open, a perforated support positioned within said casing, whereby said attachment may be positioned upon a horn or bell so as to allow the structure upon which the same is positioned to be gripped by said perforated support, thus retaining said attachment in a set position, and said attachment being adapted to collect and harmonize the secondary sound waves issuing therefrom to project the sound waves in increased volume. 120

3. A horn or bell attachment comprising a casing, said casing having a head formed upon one end, said head having an open- 130

ing formed therethrough, a conical flange formed upon said head and surrounding said opening, the opposite end of said casing being flared to form a bell, a perforated support positioned within said casing, whereby a horn may be injected through the support and through said flange, thus allowing said sleeve and support to grip the horn for holding said attachment against dis-
placement, while the attachment will receive and harmonize and then project with increased volume the secondary sound waves issuing from the horn.

5

In testimony whereof I affix my signature in the presence of two witnesses.
